UNITED STATES PATENT OFFICE.

MARTIN SCHICHTL, OF NORTH YAKIMA, WASHINGTON.

DESIGN FOR A CLAMP-FRAME FOR VEHICLE-TONGUE SUPPORTS.

SPECIFICATION forming part of Design No. 32,177, dated January 30, 1900.

Application filed December 18, 1899. Serial No. 740,830. Term of patent 14 years.

To all whom it may concern:

Be it known that I, MARTIN SCHICHTL, a citizen of the United States, residing at North Yakima, in the county of Yakima and State 5 of Washington, have invented and produced a new and original Design for a Clamp-Frame for a Vehicle-Tongue Support, of which the following is a specification.

The invention relates to a new and original 10 design for a clamp-frame for a vehicle-tongue support; and it has for its object to provide a design of this character which will be both useful and ornamental.

The essential feature of the design resides 15 in a clamp-frame composed of two approximately U-shaped sides converged at one end of the frame and united to provide a single arm and extended at the other end of the frame to provide a pair of arms, said sides 20 being connected at the inner ends of the pair of arms by a transverse portion having an opening.

In the drawings, Figure 1 is a perspective view of a clamp-frame, showing my new and 25 original design. Fig. 2 is a transverse sectional view.

Referring to the drawings, 11 designate approximately U-shaped sides of a clamp-

frame, said sides being converged at 2 at one end of the frame and extended to form an arm 30 3, which is enlarged to form a head 4. The head 4 is provided with an opening, and the sides 1 are extended at the other end of the frame to form a pair of approximately parallel arms 5, having heads 6 at their upper or 35 outer ends. The inner faces of the heads are provided with ribs or corrugations 6 and tapering projections 6^a, and the sides of the frame are connected at the lower or inner ends of the arms 5 by a transverse portion 7, having 40 an opening 8, located between the sides of the frame. The tapering projections 6^a, which extend from the corrugated faces of the heads, are substantially triangular and are provided with inclined upper and lower 45 faces.

What is claimed is—

The design for a clamp-frame, as herein shown and described.

In testimony that I claim the foregoing as 50 my own I have hereto affixed my signature in the presence of two witnesses.

MARTIN SCHICHTL.
